UNITED STATES PATENT OFFICE.

FRED E. WEED, OF COLUMBIA, MISSOURI.

AUTOMATIC PAPER FEEDER.

1,412,323.

Specification of Letters Patent. Patented Apr. 11, 1922.

Application filed October 18, 1920. Serial No. 417,668.

To all whom it may concern:

Be it known that I, FRED E. WEED, citizen of the United States, residing at Columbia, in the county of Boone and State of Missouri, have invented certain new and useful Improvements in Automatic Paper Feeders, of which the following is a specification.

This invention relates to feeding mechanism for paper printing and folding machines or devices.

The principal object of the invention is to provide improved feeding mechanism wherein the sheets of paper will be fed successively to the printing press or folding machine and wherein the feed will be uniform and constant and automatically regulated during such operation.

Another object of the invention is to provide mechanism of the above character which in addition to providing means to feed the sheets of paper in succession, includes improved mechanism to properly handle the bulk paper and automatically move the same into engagement with the feeding mechanism proper.

A further object of the invention is to provide improved paper feeding means which are applicable to conventional makes of printing and folding machines.

Various other objects and advantages of my invention will become apparent during the continuance of the following descriptions.

In the drawings:—

Figure 1 is a view in top plan of the improved feeding mechanism of my invention showing the same as in its preferred embodiment.

Figure 2 is a view in side elevation of my invention.

Figure 3 is an enlarged detailed view illustrating the paper engaging mechanism of the device, and Figure 4 is an end elevation thereof.

In reducing my invention to practice I first provide a feeding table or platform 10 which is arranged so as to slant slightly toward the forward end and positioned so that its forward end is in close proximity to the printing press or folding machine in connection with which the feeding mechanism is to be used.

At its rear end, that is the end nearest the operator, the table 10 is provided with a series of spaced brackets, bearings or other supports 11 for a drive shaft 10' which car-

ries a friction roller 12; the latter extending parallel to the adjacent edge of the table as clearly shown in Figure 1. A ratchet wheel 13 is keyed to the shaft near one end thereof while an arm 14 is loosely mounted thereon and provided with a pawl 15 which normally engages the ratchet teeth of the wheel. When oscillated by the rod 16, the pawl 15 being engaged with the ratchet teeth of the wheel 13 will cause rotation of the shaft. In operation the rod 16 is adapted to be connected to suitable mechanism on the printing press or folding machine in connection with which the invention is used.

With a view to providing means to render the roller 12 inoperative at certain times and to control the operation thereof automatically I provide the roller with a second loose arm 17 adjacent to arm 14 whose outer or engaging face 18 is arranged in alignment with a stud 19 with a pawl 15. In other words, the arm 17 may be moved so as to bring its engaging face 18 into engagement with and raise the stud 19 so as to move the pawl 15 out of engagement with the teeth of the wheel 13.

In order to control the arm 17 automatically, suitable mechanism is arranged on the table 10 to be engaged by the paper. This mechanism consists of opposed bearings 20 arranged near the front end of the table 10 which carry a laterally disposed shaft 21. One end of the shaft 21 is provided with a crank arm 22 which in turn is connected to one end of a connecting rod 23. The other end of the connecting rod 23 is secured to the arm 17 as at 24. Shaft 21 is further provided at a point intermediate its ends with a curved finger 25 on the outer end of which is mounted a roller 26. When the bulk of paper reaches its proper position on the table 10, it becomes engaged with and raises the roller 26 thus oscillating the finger 25, imparting a partial turn to the shaft 21, rocking the crank 22, reciprocating the connecting rod 23 and moving the arm 17 so that the same lifts the pawl 15 out of engagement with the teeth of the ratchet wheel 13.

Endless belts 27 of tape or other suitable material have their upper lengths operating on the table 10 and travel over the roller 12. The roller 12 operates the belts 27 by frictional engagement so as to cause the same to move the bulk of paper forwardly on the table 10. When the paper has been moved a sufficient distance it becomes engaged with

the roller 26 thus causing the roller 12 and the belts 27 to become inoperative in the manner hereinbefore described.

Tracks 28 are positioned on the table 10 opposite to each other and slightly in advance of the central transverse axis of the table 10 and on which operates a cross bar 29. Spaced fingers 30 are carried on the cross bar and are equipped with rollers 31 which have tires 32 of rubber or other suitable material which are adapted to engage the top sheet of paper and cause the same to be fed forwardly on the table to the guides of the printing press or folding machine in connection with which the invention is used. In order to operate the cross bar 29 I further provide side arms 33 one end of which connects with the cross bar and the other end to suitable mechanism on the printing press or folding machine. Upon being reciprocated the arms 33 cause the cross bar 29 to be moved forwardly and backwardly on the tracks 28 and the rollers 31 being engaged with the paper will cause the latter to be properly fed. In order to insure a positive feed the rollers 31 are preferably of the ratchet type so that they will not turn during the forward movement of the cross bar 29 yet turn during the rearward movement thereof.

The bulk of paper which is first placed on the table 10 near the roller 12 is held in position by rollers 34 that are carried on spring arms 35 from a common carrier 36.

Having thus fully described my invention what I claim as new and desire to secure by Letters Patent is:—

1. A device of the character described comprising a table, paper carrying means arranged in spaced relation on said table and adapted to travel longitudinally with respect thereto, tracks positioned on said table in opposed relation, a cross bar loosely mounted

on said tracks, a plurality of fingers carried by said cross bar, stationary rollers carried by said fingers, and means to move said cross bar and the mechanism carried thereby backwards and forwards with respect to said table. 45

2. A device of the character described comprising a table, a friction roller positioned at one end of said table, said table being provided with spaced openings near its other end, rollers mounted in said openings, a series of endless belts arranged to operate on said first and second named rollers and extending longitudinally with respect to said table, a gear wheel keyed to said first named friction roller, means rockably mounted on said friction roller adapted to engage and rotate said gear wheel, and means operable from a point on said table in advance of said endless belts whereby said last named means may be disengaged from said gear wheel. 50 55

3. An automatic paper feeder comprising a feed table having conveyor means for supporting and feeding paper sheets longitudinally of the table, said feeding means including a main drive shaft at one end of the table, a rotatable shaft journaled crosswise of the opposite end of the table, a vertically movable roller element carried by said shaft, a ratchet wheel fixed to the said drive shaft, an arm mounted loosely on said shaft for turning movement, a pawl carried by said arm and normally engaging a ratchet wheel, said pawl being provided with a projection, a second arm loosely mounted on said shaft for swinging movement, said second arm being adapted to engage the projection for raising the pawls from the ratchet wheel, and a trip connection between said pawl engaging arm and the said rotatable shaft. 65 70 75 80 85

In testimony whereof I affix my signature. 85
FRED E. WEED.
